(57) **CLAIM**

The ornamental design for an analysis chip for biochemical inspection machine, as shown and described.

DESCRIPTION

FIG. 1 is a top-front-right perspective view of an analysis chip for biochemical inspection machine showing my new design;

FIG. 2 is a top-rear-left perspective view thereof;

FIG. 3 is a front view thereof;

FIG. 4 is a rear view thereof;

FIG. 5 is a right side view thereof;

FIG. 6 is a left side view thereof;

FIG. 7 is a top plan view thereof;

FIG. 8 is a bottom plan view thereof;

FIG. 9 is a sectional view taken from line 9-9 in FIG. 3; and, FIG. 10 is a sectional view taken from line 10-10 in FIG. 3. The broken line showing portions of the analysis chip for biochemical inspection machine form no part of the claimed design.
